ABSTRACT: The relaxing apparatus of the present invention comprises a treating bath having a plurality of hurdle projections mounted on the inside surface of the treating bath and a cylindrical rotor facing the inside surface of the treating bath, the rotor is reciprocally rotatable at a predetermined angle, preferably 20° to 45° and has a plurality of paddle projections mounted on the peripheral surface of the rotor. The paddle projections are effective for paddling a treating liquid in the treating bath so as to exert a crumpling action to the material charged in the treating bath. The hurdle projections are effective for enforcing the crumpling action presenting an obstacle to movements of the material and treating liquid. The material can be continuously and sufficiently relaxed in the treating liquid by the crumpling action.

APPARATUS FOR CONTINUOUSLY RELAXING TEXTILE MATERIAL IN A TREATING LIQUID

The present invention relates to an apparatus for continuously relaxing a textile material in a treating liquid, more particularly relates to an apparatus for continuously relaxing a textile material by exerting a mechanical crumpling action on the material in a treating liquid in order to eliminate residual inner stress of the material and/or sufficiently shrink the material, whereby a final product having a high-dimensional stability or a creped product is obtained.

It is well-known that when a textile material is subjected to some stretching operations in spinning, twisting, knitting, weaving, scouring or dyeing process, the stretching causes the remaining of inner stress in the material. The remaining stress is so-called residual inner stress.

The residual inner stress causes a dimensional change or deformation of the material during laundering of the material and further, results in unevenness in bulkiness, appearance or hand feeling of the material. These tendencies more clearly appear in textured materials having high-extensibility.

A process for eliminating the residual inner stress from the textile material is a so-called relaxation in general. Also, a process for preparing a crepe product from a fabric made of hard twist yarns or highly shrinkable yarns is a so-called relaxation.

Generally, the relaxation for increasing the dimensional stability of textile materials, particularly filamentary fabrics, and/or for creping textile fabrics, is carried out by using a rotary-washer-type relaxer or star-frames in a treating bath, or by method of a book-fold form system or loop- or reeled-form system. These conventional processes create a good relaxing effect, respectively. However, these conventional processes are inefficient due to their noncontinuity. Particularly, the relaxation process of the rotary-washer-type relaxer has a defect such as easy formation of crease-marks on the material. In order to obviate the above-mentioned disadvantages of the conventional relaxation, various improvements, for example, a process for continuously relaxing the material in an open form, are provided.

Apparatuses for continuously relaxing the material are required to satisfy the following requirements:

1. the material is extended in as low a stress as possible during processing,
2. the material is uniformly heated and maintained at a desired constant temperature,
3. the material is subjected to a suitable mechanical crumpling action,
4. the material is subjected to relaxation for a time sufficient enough for relaxing the material,
5. cost of the relaxation apparatus and driving cost of the apparatus are low, and
6. area required for the relaxing apparatus is small.

However, conventional relaxing apparatuses satisfying all of the above-stated requirements cannot be found.

An object of the present invention is to provide an apparatus for continuously relaxing openly formed textile material in a treating liquid having low-equipment cost, low-operating cost, a small operating area and an excellent relaxing effect.

The apparatus of the present invention comprises the following elements:

1. a treating bath vessel, for containing a treating liquid, provided with an inside bottom having an inside semicylindrical peripheral surface,
2. a reciprocally rotatable cylindrical rotor being disposed in the treating bath vessel in a manner wherein a peripheral surface of the cylindrical rotor is in parallel with respect to the inside surface of the treating bath vessel,
3. a plurality of hurdle projections being mounted on the inside surface of the treating bath vessel in a manner wherein the hurdle projections extend along the inside surface of the treating bath vessel in parallel with respect to a cylindrical axis of the semicylindrical inside bottom, and

4. a plurality of paddle projections being mounted on the peripheral surface of the cylindrical rotor in a manner wherein the paddle projections extend along the peripheral surface of the cylindrical rotor in parallel with respect to a cylindrical axis of the cylindrical rotor.

Further features and advantages of the apparatus of the present invention will be seen in detail from the following description, referring to the accompanying drawings, in which,

10 FIG. 1 is a schematic perspective side view of an embodiment of the apparatus of the present invention, and

15 FIG. 2 is a schematic side view showing embodiments of a cylindrical rotor and paddle projections in the apparatus of the present invention.

15 Referring to FIG. 1, a treating bath vessel 1 usable for containing a treating liquid is provided with a bottom 2 having an inside semicylindrical peripheral surface. Nine hurdle projections 3 are mounted on the inside surface of the treating bath vessel 1. The hurdle projections 3 have a substantially triangular cross-sectional profile and extend along the inside surface of the treating bath vessel 1 in parallel with respect to a cylindrical axis of the semicylindrical inside surface of the treating bath vessel 1.

20 25 A cylindrical rotor 4 is disposed at a substantially center portion of the treating bath in a manner wherein a peripheral surface of the cylindrical rotor 4 is in parallel with respect to the inside surface of the treating bath vessel 1. Nine paddle projection 5 are mounted on the peripheral surface of the

30 35 cylindrical rotor 4 in parallel with respect to a cylindric axis 6 of the cylindrical rotor 4. The paddle projections 5 are disposed so as to face the inside surface of the treating bath vessel 1, but not disposed at the top portion of the cylindrical rotor 4 which faces the upper opening of the treating bath vessel 1. The paddle projections 5 have a substantially triangular cross-sectional profile.

35 The cylindrical rotor 4 is reciprocally rotatable around the cylindrical axis 6 in a direction shown by arrows 7 and 8 by a predetermined rotation angle.

40 45 FIG. 1 shows means for rotating the cylindrical rotor 4, but the rotating means is not limited to the means of FIG. 1. In FIG. 1, two reciprocally rotating plates 9 are fixed on both side surfaces of the cylindrical rotor 4, and the top end 10 of the rotating plate 9 is connected to a motor 12 through a reciprocally moving arm 13, a flywheel 12a, a speed changing means 12c and a speed reducing means 12b. The arm 13 can be reciprocally moved in directions shown by arrows 14 and 15 with rotation of the flywheel 12a by way of the motor 12c.

50 55 The movement of the arm 13 can rotate the rotating plates 9 reciprocally. In this case, the rotation angle of the rotating plate 9, which may be adjusted by the dimensions of the diameter of the flywheel 12a, is in a range from 20° to 45°, preferably from 30° to 40°. The rotation of the rotating plate 9, which may be adjusted by speed of the rotor 12c, speed changing ratio of the speed changing means 12c and reducing ratio of the speed reducing means 12b, is 50 to 150 times/minute, preferably 80 to 120 times/minute.

60 65 The hurdle projections 3, illustrated in FIG. 1, have a substantially isosceles triangular cross-sectional profile, and project at substantially right angles on the inside surface of the treating bath vessel. A top portion of the hurdle projections 3 is rounded off.

65 70 Referring to FIG. 2, a paddle surface 5a of the paddle projections 5, that is, a front surface with respect to a direction indicated by an arrow 17 along which the material to be relaxed is advanced, is substantially parallel with respect to a plane 16 on which the cylindrical axis 6 of the cylindrical rotor 4 and a top end 5c of the paddle projections 5 are lain and a back surface 5b of the paddle projections 5 meet the paddle surface 5a at an acute angle α , preferably 20° to 45°. The top portion of the paddle projections 5 is rounded off.

75 Height of the paddle and hurdle projections may be adjusted as desired according to purpose of relaxing, kind of material to be relaxed and speed of relaxing. In general, these

heights are in a range from one-fifth to one-half radius of the cylindrical rotor 4.

Distance between the peripheral surface of the cylindrical rotor 4 and the semicylindrical inside surface of the treating bath may be adjusted as desired according to purpose of relaxing, kind of material to be relaxed and speed of relaxing. Usually, the distance is in a range from two-thirds to 1½ radius of the cylindrical rotor 4.

Number of the hurdle and paddle projections may be determined as desired according to purpose of relaxing, kind of material to be treated and speed of relaxing. Generally, the number is in a range from 5 to 12, preferably 8 to 10, and may be the same as each other or different from each other.

Referring to FIG. 1, a wetting means 24 consisting of a bath 22 and a roll 23 is disposed at an entrance side of the treating bath vessel 1, and a feeding means consisting of a feeding roll 25 and a pressing roll 26 and a delivering means consisting of delivering rolls 28 and 29 are disposed above the treating bath vessel 1.

Further, means for supplying water, steam and treating liquid from respective sources may be connected to the wetting bath vessel 22 and the treating bath 1.

The relaxation operation for the textile material and its effect by using the apparatus of the present invention will be described in detail referring to FIG. 1, hereinafter.

When the feeding roll 25 is driven, the material 21 is fed into the wetting means 24 containing a treating liquid at an open width condition, wetted with the treating liquid, and then charged into the treating bath vessel 1 through the feeding roll 25 and the pressing roll 26. The treating bath vessel 1 contains a treating liquid 31 adjusted to a desired temperature. The charged material 21 is accumulated under a tensionless condition in a treating space 32 formed between the inside surface of the treating bath vessel 1 and the peripheral surface of the cylindrical rotor 4.

Next, the cylindrical rotor is driven into a reciprocal rotation in both directions illustrated by the arrows 7 and 8 at a preadjusted rotation angle, preferably 20° to 45°. When the cylindrical rotor 4 is rotated in the direction of the arrow 7, the paddle surfaces 5a of the paddle projections 5 paddle the treating liquid so that the paddle treating liquid exerts a vigorous crumpling action to the accumulated material 21, whereby the accumulated material 21 is moved in the direction of the arrow 7. Next, the cylindrical rotor 4 is rotated in the direction of the arrow 8, the back surfaces 5b of the paddle projections 5 slightly paddle the treating liquid so as to exert a weak action to the material 21. In such paddling, since the back surfaces 5b are inclined so as to meet the direction of the arrow 8 at an acute angle, the paddling effect of the back surfaces 5b is by far, less than that of the paddle surfaces 5a. Therefore, the material 21 is not moved in the direction of arrow 8.

The hurdle projections 3 stand in the way of the material 21 and the treating liquid 31 so as to obstruct the movement of the material 21 and the treating liquid 31. That is, the accumulated material 21 receives a vigorously exerted crumpling action by the paddle projections 5 under a condition wherein the smooth movements of the material 21 and treating liquid 31 are obstructed by the hurdle projections 3. Therefore, the crumpling effect of the paddle projections 5 is further increased by the hurdle projections 3.

By the above-stated manner, the accumulated material 21 can be intermittently moved in the direction of the arrow 7 in the treating space 32. When an end of the material 21 reaches

the exit portion of the treating space 32, the end of the material 21 is drawn up by the delivery rolls 28 and 29 in order to withdraw the material 21 from the treating bath vessel 1.

Velocities of the feeding roll 25 and the delivering roll 28 must be adjusted so as to retain the material in the treating bath vessel 1 for a desired period.

As is clear in the above-stated description, the textile material can be sufficiently and continuously relaxed by using the apparatus of the present invention under an open width condition.

What is claimed is:

1. An apparatus for continuously relaxing textile material in a treating liquid comprising:
  1. a treating bath vessel provided with an inside bottom having an inside semicylindrical peripheral surface with a horizontal axis, closed ends and a top with an opening,
  2. a reciprocally rotatable cylindrical rotor disposed in said treating bath vessel with its axis horizontal and a peripheral surface in parallel with respect to said inside surface of said treating bath vessel,
  3. a plurality of hurdle projections disposed on said inside surface of said treating bath vessel, said hurdle projections extending axially along said inside surface of said treating bath vessel with respect to the cylindrical axis of said semicylindrical inside bottom,
  4. a plurality of paddle projections disposed on said peripheral surface of said rotor, said paddle projections extending axially along said peripheral surface of said cylindrical rotor with respect to the cylindrical axis of said cylindrical rotor
  5. means for continuously oscillating said rotor about its axis, and
  6. means for continuously feeding hard textile material into said treating bath vessel through said opening at one side of said rotor and withdrawing it from said treating bath vessel at the other side of said rotor.
2. An apparatus as claimed in claim 1, wherein said hurdle projections have a substantially triangular cross-sectional profile.
3. An apparatus as claimed in claim 1, wherein said paddle projections have a substantially triangular cross-sectional profile.
4. An apparatus as claimed in claim 1, wherein a paddle surface of said paddle projections is substantially parallel with respect to a plane, passing through the axis line of said cylindrical rotor and the top end of said paddle projections.
5. An apparatus as claimed in claim 1, wherein said paddle projections have a height in a range from one-fifth to one-half of the radius of said cylindrical rotor.
6. An apparatus as claimed in claim 1, wherein said hurdle projections have a height in a range from one-fifth to one-half of the radius of said cylindrical rotor.
7. An apparatus as claimed in claim 1, wherein said peripheral surface of said cylindrical rotor is spaced from said inside surface of said treating bath vessel at a distance of two-thirds to 1½ of the radius of said cylindrical rotor.
8. An apparatus as claimed in claim 1, wherein said reciprocal rotation angle of said cylindrical rotor is in a range from 20° to 45°.
9. An apparatus as claimed in claim 1, wherein said reciprocal rotation angle of said cylindrical rotor is in a range from 30° to 40°.
10. An apparatus as claimed in claim 1, wherein said oscillating means oscillates said rotor in the range from 50 to 150 times a minute.
